[57] CLAIM

The ornamental design for a tire, as shown and de-
scribed.

DESCRIPTION

FIG. 1 is a front elevation view of the tire of FIG. 3
showing my new design;FIG. 2 is a side elevation view of the tire of FIG. 3
showing my new design; and,FIG. 3 is a perspective view of a tire showing my new
design, it being understood that the tread pattern is
repeated throughout the circumference of the tire, the
opposite side being substantially the same as that illus-
trated.Fig.1
